UNITED STATES PATENT OFFICE.

JOHN AUSTIN MORAN, OF BROOKLYN, NEW YORK.

GUN-DISAPPEARING APPARATUS.

1,399,395.

Specification of Letters Patent.

Patented Dec. 6, 1921.

Application filed December 30, 1919. Serial No. 348,271.

To all whom it may concern:

Be it known that I, JOHN AUSTIN MORAN, a citizen of the United States, and resident of the borough of Brooklyn, New York city, 5 in the county of Kings and State of New York, have invented certain new and useful Improvements in a Gun-Disappearing Apparatus, of which the following is a specification.

10 This invention relates to a gun disappearing apparatus, which can easily be installed in a vessel, that was not originally intended to be provided with guns.

15 The disappearing apparatus is supported on a turntable, which is turned by means of an electric motor. The supporting devices of the gun are actuated by pistons in hydraulic cylinders. The water for the cylinders is provided by a pump in the engine 20 room of the vessel.

Figure 1 represents a side elevation of a vessel having portions broken away with a partial section of Fig. 2 on the line 1, 1, and a pair of side elevations of the gun disappearing apparatus with their guns, Fig. 3 is an enlarged fragmentary portion of Fig. 1; Fig. 4 shows a partial top plan view of Fig. 3 and section of said figure on the line 4, 4; Fig. 5 represents a left hand view and partial section of Fig. 4 on the broken line 5, 5; Figs. 6, 7 and 8 show horizontal axial sections of a three way valve with fragmentary portions of their pipe connections, and Fig. 9 is an enlarged portion of Fig. 3.

35 A vessel 20 is indicated with the engine room 21, the upper deck 22 and the gun chambers 23 and 24. The chambers have the end walls 25, 26 and the side walls 28 29. Openings 30 are formed in the roof of 40 each chamber for detachable covers not shown.

In each of the chambers 23, 24 is indicated an annular bed plate 35 which is fastened to the deck 36. A ball bearing 45 race 37 and bearing 38 with the heel 39 are formed in the bed plate 35. A turntable 40 has formed therein with the central opening 41, the ball bearing race 42 and the flange 43. Bevel gear teeth 44 are formed 50 with the turntable 40. The lower face of the flange 43 is slightly above the upper face of the bearing 38. A ring 45 is bolted to the heel 39. The coaction of the flange 43 and ring 45 constitutes a locking means for the 55 turntable and prevents it tipping or disengaging from its bed plate 35 when the gun

is fired, but permits the rotation of the turntable at all times. Ball bearings 46 are located between the races 37 and 42. In each of the chambers 23, 24 is provided a 60 journal bracket 47 and adjacent to the chambers are secured journal brackets 48 each with the horizontal bearing 49 and the vertical bearing 50. A shaft 52 is journaled in each journal bracket 47 and in its accompanying bearing 49.

A journal bracket 54 having the bearing 55 extends below the upper deck 22. A vertical shaft 56 is journaled in the bearings 50 and 55. A bevel gear 57 on one end 70 of the shaft 52 meshes with the bevel teeth 44. A bevel gear 62 fastened on the other end of the shaft 52 meshes with the bevel gear 63 fastened to one end of the shaft 56. A bevel gear 64 is fastened to the other 75 end of the shaft 56. An electric motor 65 extends below the upper deck 22 and has secured to its armature shaft the bevel gear 66, which meshes with the bevel gear 64. An electric controller 67 having the handle 80 68 is provided for the electric motor 65. Wires, not shown, for electric current are connected to said controller 67.

85 A pair of hydraulic cylinders are indicated at 70. Each of the cylinders has formed therewith a supporting bracket 71 with the foot 72. The latter is bolted to the turntable 40. A piston 73 with piston rod 74 is provided for each cylinder 70. A cross head 75 is fastened to one end of each piston 90 rod 74.

Guides are shown with the members 76 and 76^a. The latter have formed therewith the brackets 77 having the feet 78. The latter are bolted to the turntable 40. A pair 95 of journal brackets 82 and the cradles 83 and 84 are fastened to the turntable 40.

A disappearing gun 86 is indicated with its pivot 87 and socket 88. Arms 89 extend from the socket 88. The outer ends 100 of the arms 89 are pivoted to the journal brackets 82 by means of the pins 90. Links 91 have each one end pivoted to the socket 88 by means of the pins 92 and their other ends are pinned to the cross heads 75 by 105 means of the pins 93.

To raise and lower the guns 86 the following hydraulic appurtenances are provided. In the engine room 21 are located a pair of pumps 95, each with a suction pipe 96 110 that leads to the bilge and discharge piping 97. A pipe 98 with the valve 99 is connected

to each line of piping 97, to enable the pipe 97 to be drained. The piping 97 has connected thereto the T 103.

A branch pipe 104 extends from the T 103 and is provided at its upper end with a stuffing box 105 which has its vertical axis in line with the vertical axial center of the turntable 40. An elbow 106 is connected to the top end of the stuffing box 105. Piping 107 and 108 with the three-way valve 109 is connected to the elbow 106. The valve 109 has also connected thereto the pipe 110. A hollow plug with ports, as to be described, for the valve 126, is provided for the valve 109. The piping 108 is connected to the back end of each of the cylinders 70. An operating rod 116 with the operating hand wheel 117 is connected to the hollow plug in the valve 109. A pipe 119 with the elbow 120 extends from the T 103. A branch pipe 122 extends from the elbow 120 and has extending therefrom the piping 123 and 124 similar respectively to the piping 107 and 108. A stuffing box 125 similar to 105 is connected to the piping 124. Piping 125^a leads from the stuffing box 125 to the front ends of the cylinders 70. A three way valve 126 similar to 109 is connected to the piping 123 and 124. A hollow plug valve 111 with the ports 112, 112^a and 112^b is seated in the valve 126.

An operating rod 127 and operating hand wheel 128 respectively similar to 116 and 117 are provided for the three-way valve 126. A pipe 132 similar to the pipe 110 extends from the three-way valve 126. The pipes 110 and 132 are connected by the piping 133 and from the latter extends the discharge pipe 135. Drain piping 136 extends from the chamber 23 and drain piping 137 extends from the chamber 24.

To operate the gun disappearing apparatus, the covers, not shown, for the openings 30 of the gun chambers 23 and 24 are removed.

The guns 86 in their lowered position are indicated in dotted lines in Fig. 3.

To elevate the guns to their upper and firing position the pumps 95 are started, by means of which water will be forced up the discharge piping 97. Upon opening the three-way valve 126 by means of the operating hand wheel 128, to locate the hollow plug 111 to the position shown in Fig. 6, that is to say, with the port 112 in line with the port 113 and the port 112^b in line with the port 114, water will flow through the piping 123, 124 and 125^a in the direction of the arrow A and enter the front end F of the cylinders 70. By this means the pistons 73 and cross-heads 75 will move in the direction of the arrow D.

This will cause the links 91 to swing from their positions shown in dotted lines in Fig. 3 to their elevated positions shown in full

lines in said figure. At the same time the guns 86 will be raised from their lower position on the cradles 83 and 84 shown in dotted lines in Fig. 3, in the gun chambers 23 and 24, to their elevated or raised positions 70 shown in full lines in said figure.

The hollow plug 111 may now be turned to the position shown in Fig. 7 with all the ports 112, 112^a and 112^b closed and the water will be retained in the cylinders 70 with the pistons 73 adjacent to the back ends D. If it is desired to lower the guns the hollow plug 111 of the valve 126 is turned to the position shown in Fig. 8 with the port 112^a in line with the port 114 and the port 112^b 75 in line with the port 115, when the water in front of the piston 73 will flow through the piping 125^a, 124, valve 126, pipe 132 and piping 135 to be discharged. At the same time the valve 107 is operated as described 80 for the valve 126 and water pressure will be brought between the pistons 73 and the back ends B of the cylinders 70. By this means the guns 86 will be swung to their lowered position on the cradles 83 and 84. 90

When the guns are in their raised position, they may be located in different radial positions to point them when required by turning the turntables 40. The turntables 40 are turned by means of the electric motors 65 and the gearing interposed between said motor and the teeth 44 of the turntables. When the turntable is being turned, the piping 108 and 125^a revolve around the axial centers of the stuffing boxes 105 and 125, 100 the latter permitting the revolutions of said piping, the vertical axial line of the stuffing box 125 being in line with the vertical axial line of the stuffing box 105.

Having described my invention what I 105 desire to secure by Letters Patent and claim is:

1. In a gun disappearing apparatus the combination of a gun, a socket for the pivot of the gun, arms extending from the socket, a pair of links with the upper end of each pivoted to said socket, a turntable, journal brackets supported on the turntable, the arms of the socket pivoted to said journal brackets, a pair of cylinders supported on the turn table, a piston for each cylinder, a piston rod for each piston, pairs of guides on the turntable, a cross head for each pair of guides, said cross head connected to its accompanying piston rod, the lower ends of 115 said links pivoted to said cross heads and means to force a fluid into each end of both cylinders. 120

2. In a gun disappearing apparatus the combination of a gun, a turntable, a pair of hydraulic cylinders on the turntable, a piston with a piston rod for each cylinder, connections between each piston rod and the gun to locate the latter at different levels, a pump, discharge piping for the pump, 125 130

branch pipes extending from the discharge piping, piping extending from one of the branch pipes to one end of the cylinders, a stuffing box for the latter piping, piping extending from the other branch pipe to the other ends of the cylinders and a stuffing box for the latter piping, the longitudinal axes of the stuffing boxes and the axial center line of the turntable coincident with one another.

3. In a gun disappearing apparatus the combination of a gun, a turntable, a pair of hydraulic cylinders on the turntable, a piston with a piston rod for each cylinder, connections between each piston rod and the gun to locate the latter at different levels, a pair of cradles on the turntable to support the gun in its lowered position, a pump, discharge piping for the pump, branch pipes extending from the discharge piping, piping extending from one of the branch pipes to one end of the cylinders, a three way valve and a stuffing box for the latter piping, piping extending from the other branch pipe to the other ends of the cylinders, a three-way valve and a stuffing box for the latter piping, the longitudinal axes of the stuffing boxes and the axial center line of the turntable coincident with one another.

4. The combination in a vessel of a gun chamber, a turntable in the chamber, hydraulic cylinders on the turntable, a piston for each cylinder, a pair of journal brackets supported on the turntable, a gun, a socket for the pivot of the gun, a pair of arms extending from said socket, the outer ends of the arms pivoted to said journal brackets, connections between the said pistons and the gun to locate the latter at different levels, a pump, piping to lead water under pressure from the pump to the cylinders to reciprocate the pistons therein and means to turn the turntables.

5. The combination in a vessel of a gun chamber, a turntable in the chamber, means to turn the turntable, a pair of hydraulic cylinders on the turntable, a pump, piping leading from the pump to both ends of the cylinders, stuffing boxes with their longitudinal axes coincident with the axial center line of the turntable connected to the piping to permit the revolution of a portion thereof when the turntable is turning, a piston in each cylinder, a gun and connections between the gun and said pistons to locate the gun at different levels.

6. The combination in a vessel of a pair of gun chambers below the upper deck of the vessel, a turntable for each chamber, electric means to turn each turntable independently of each other, a pair of pumps in the vessel, a pair of hydraulic cylinders on each turntable, a pair of journal brackets on each turntable, a gun for each gun chamber, a socket for the pivot of each gun, a pair of arms extending from each socket with their outer ends pivoted to the journal brackets of its accompanying turntable, a piston in each cylinder, linked connections between each piston and its accompanying gun socket to locate the guns at different levels, piping connecting each pump and a pair of said hydraulic cylinders and stuffing boxes in the piping to permit portions thereof to revolve with the rotations of the turntables.

Signed at the borough of Brooklyn, city of New York, in the county of Kings and State of New York, this 18th day of December A. D. 1919.

JOHN AUSTIN MORAN.
